UNITED STATES PATENT OFFICE.

EDWIN S. PRIDHAM AND PETER L. JENSEN, OF OAKLAND, CALIFORNIA, ASSIGNORS
TO THE MAGNAVOX COMPANY, OF OAKLAND, CALIFORNIA, A CORPORATION OF
ARIZONA.

DESIGN FOR A CABINET FOR RADIO RECEIVING APPARATUS.

Application filed September 17, 1924. Serial No. 10,798. Term of patent 14 years.

To all whom it may concern:

Be it known that we, EDWIN S. PRIDHAM and PETER L. JENSEN, citizens of the United States, residing at Oakland, county of Alameda, and State of California, have invented a new, original, and ornamental Design for Cabinet for Radio Receiving Apparatus, of which the following is a specification, reference being had to the accompanying drawing, forming part thereof.

Fig. 1 is a perspective view of a cabinet

for radio receiving apparatus, showing our new design, with the doors at the front thereof in open position.

Fig. 2 is a perspective view of the same cabinet with the doors in closed position.

We claim:

The ornamental design for a cabinet for radio receiving apparatus, substantially as shown.

EDWIN S. PRIDHAM.
PETER L. JENSEN.
